CLAIM

The ornamental design for a shipping box, as shown and described.

DESCRIPTION

FIG. 1 is a perspective view of a shipping box showing our new design;

FIG. 2 is a front view of the shipping box of FIG. 1.

FIG. 3 is a rear view of the shipping box of FIG. 1, wherein the portions of the drawings shown in broken lines, i.e., the broken line edges of the box, are to show environmental boundaries that form no part of the claimed design.

FIG. 4 is a left side view of the shipping box of FIG. 1, wherein the portions of the drawings shown in broken lines, i.e., the broken line edges of the box, are to show environmental boundaries that form no part of the claimed design.

FIG. 5 is a right side view of the shipping box of FIG. 1, wherein the portions of the drawings shown in broken lines, i.e., the broken line edges of the box, are to show environmental boundaries that form no part of the claimed design.

FIG. 6 is a top view of the shipping box of FIG. 1, wherein the portions of the drawings shown in broken lines, i.e., the broken line edges of the box, are to show environmental boundaries that form no part of the claimed design.

FIG. 7 is a bottom view of the shipping box of FIG. 1, wherein the portions of the drawings shown in broken lines, i.e., the broken line edges of the box, are to show environmental boundaries that form no part of the claimed design; and,

FIG. 8 is a further front view of a portion of the shipping box of FIG. 1, wherein the broken line edges of the box have been removed for clarity and the portion of the drawings shown in broken lines, i.e., the broken line encircling the design, are to show environmental boundaries that form no part of the claimed design.

The scope of the claimed design is not limited to having the shape of the box shown in broken lines in the drawings. The claimed design can be on a box of any size or shape.

The even-length broken lines depict the edges of the box and form no part of the claimed design. The dot-dash broken lines depict the boundaries of the claimed design and form no part thereof.

1 Claim, 7 Drawing Sheets
